UNITED STATES PATENT OFFICE.

GEORGE P. WIGGINTON, OF KALAMAZOO, MICHIGAN, ASSIGNEE TO KALAMAZOO LOOSE LEAF BINDER CO., OF KALAMAZOO, MICHIGAN.

LOOSE-SHEET DEVICE.

1,313,933.

Specification of Letters Patent. Patented Aug. 26, 1919.

Application filed May 7, 1917. Serial No. 167,069.

To all whom it may concern:

Be it known that I, GEORGE P. WIGGINTON, a citizen of the United States, residing at the city and county of Kalamazoo, State 5 of Michigan, have invented certain new and useful Improvements in Loose-Sheet Devices, of which the following is a specification.

This invention relates to improvements in 10 loose sheet devices.

My improvements are especially designed to facilitate the handling of loose sheets, by which term I contemplate cards and the like, in accounting or record systems.

15 The main objects of this invention are:

First, to provide an improved loose sheet device which facilitates the handling or manipulation of loose record sheets.

Second, to provide an improved loose 20 sheet device which facilitates the use of loose sheets and at the same time provides a holder therefor adapted as a cabinet unit.

Third, to provide an improved loose sheet device of large capacity and at the same 25 time convenient to use.

Fourth, to provide an improved loose sheet device adapted as a cabinet unit in which all of the sheets are readily accessible.

Further objects, and objects relating to 30 structural details, will definitely appear from the detailed description to follow.

I accomplish the objects of my invention by the devices and means described in the following specification. The invention is 35 clearly defined and pointed out in the claims.

A structure which is a preferred embodiment of my invention is clearly illustrated in the accompanying drawing, forming a part of this specification, in which:

40 Figure I is a front perspective view of a cabinet structure embodying my improvements.

Fig. II is a plan view of one of the units or sheet holder devices withdrawn from the 45 cabinet, the same being adjusted as a drawer.

Fig. III is a detail longitudinal section on a line corresponding to line 3—3 of Fig. II.

Fig. IV is a similar detail longitudinal 50 section with the device adjusted for the manipulation of the sheets.

Fig. IV^A is a perspective view of the removable sheet support removed from the holder.

Fig. V is a perspective view of one of the 55 units, adjusted as in Fig. IV, with the sheets removed.

Fig. VI is a detail longitudinal section on a line corresponding to line 6—6 of Fig. II, showing further details of the adjustment 60 of the sheet holder.

Fig. VII is a similar detail section, showing another adjustment of the device.

Fig. VIII is an enlarged detail perspective view on a line corresponding to line 65 8—8 of Fig. II.

Fig. IX is a detail section on a line corresponding to line 9—9 of Fig. II, showing further structural details.

Fig. X is a detail transverse section on a 70 line corresponding to line 10—10 of Fig. II, showing details of the sheet guide.

Fig. XI is a detail section corresponding to that of Fig. VII, showing a slight modification.

Fig. XII is a detail plan view of one 75 form of sheet for which the device illustrated is adapted.

In the drawings similar reference characters refer to similar parts throughout the 80 several views, and the sectional views are taken looking in the direction of the little arrows at the ends of the section lines.

Referring to the drawing, the sheets 1, 85 illustrated, are provided with spaced notches 2 and spaced holes 3, the sheets being such as are shown in my Patent #1,174,458, March 7, 1916. My present improvements are adapted for use in connection with sheets employed in accounting systems and, 90 either in connection with binders, such as illustrated in my said patent, the sheets being transferred to and from the binders as occasion requires, or independently, my present improvements constituting, where 95 desired, a complete sheet filing means without the use of other devices. The details of the sheets may be greatly varied, my improved sheet holder being adapted for use with any form or style of sheet desired.

100 In the embodiment illustrated I provide a series of four units or sheet holder devices,

designated generally by the numeral 4, and adapted when adjusted to one position to constitute drawers of a cabinet, as 5. These sheet holder devices or units 4 comprise a 5 pair of base members 6 rigidly supported by the cross pieces 7. These base members in the embodiment illustrated constitute the sides of the drawers. On these base members I pivot a pair of holder bottom members 8 and 9 adjacent the ends of the base members at 10. The holder bottom members 8 are thus supported to swing between the base members 6. The member 8 is provided with a plate 11 having a slot 13 there- 10 in, while the member 9 has a plate 14 with a pin 15 thereon engaging and sliding in the slot. These members 8 and 9 are arranged so that when collapsed to rest upon the cross pieces 7 with the inner end of the 15 member 8 overlapping the member 9 and when swung to erected position, as shown in Figs. IV and V, the edge of the member 9 is overhung by the member 8.

The slot 13 of the plate 11 is provided 20 with an offset 16 adapted to receive the pin 15 when the members are in their erected position, thereby supporting them in such position.

Members 17 and 18 are mounted on the 25 outer ends of the bottom members 8 and 9, respectively, the member 17 being hinged to the member 8 at 19, while the member 18 is rigidly mounted at right angles to the member 9. When the sheet holder is adjusted to 30 the position shown in Figs. IV and V a pair of sheet holder members is provided, which permits the sheets being shifted from one holder member to the other, as occasion requires in manipulating the sheets. When 35 the holder is adjusted as a drawer, as shown in Fig. III, these holder members 17 and 18 constitute the ends of the drawer. The member 17 is provided with a finger piece 20 for convenience in manipulating the de- 40 vice as a drawer.

The member 17 is adjustably supported by means of the link 21, which is pivoted to it at 22 and slotted at 23 to engage the clamping bolt 24 mounted on one of the base members 6. The base member is provided with a recess 25 adapted to receive a nut 26 of the clamping bolt, so that this does not interfere with the drawers being slid into the cabinet. By thus supporting the side holder member 50 17 it may be adjusted at an acute angle to its coacting bottom member, so that the upper edges of the sheets are stepped to facilitate fingering—see Fig. VII.

In the modification shown in Fig. XI, the 55 link 27 is provided with a series of teeth 28 which may be engaged with the pin 29 on the adjacent base member 6 to adjustably support the member 17.

To facilitate fingering it is sometimes de- 60 sirable to "fan" or "step" the upper edges of

the sheets arranged in the rear holder member and, to accomplish this, I provide a tapered sheet support 30—see Fig. IV^A, which may be inserted behind the sheets, as 70 shown in Fig. IV.

Where the sheet holders are to be used for sheets having notched inner edges, as shown in Fig. XII, I provide the bottoms with sheet guides 31 positioned so that the notches may be engaged therewith. The holders are 75 of sufficient width so that the sheets may be offset as desired, thus indicating selected groups. In this embodiment the guides are removable. These guides are mounted in slide ways 32 open at their inner ends so that 80 the guides may be removed or introduced by longitudinal movement. Spring pressed pins 33 are arranged below the guides to yieldingly retain them in position. This particular guide structure is the subject 85 matter of the claims in my copending application #146,762, filed Feb. 5, 1917.

My improved loose sheet device is of large 90 capacity and at the same time supports the sheets so that they are very accessible and convenient to manipulate. The structure also has the advantage of being very economical to produce, when its capacity is considered.

I have illustrated and described my 95 improvements in a simple and practical embodiment. I have not attempted to illustrate or describe various modifications in structural details, which I contemplate, as I believe the disclosure made will enable those 100 skilled in the art to which my invention relates to embody or adapt the same as conditions may dictate.

Having thus described my invention, what 105 I claim as new and desire to secure by Letters Patent, is:

1. A sheet holder adapted as a cabinet drawer and comprising spaced base members connected by cross members and constituting drawer side members, bottom members pivoted between said base members so that they may be adjusted to rest upon said cross members or to an oppositely inclined relation, and end members mounted on said bottom members, one end member being pivoted to the outer edge of one bottom member 110 for adjustment relative thereto.

2. A sheet holder adapted as a cabinet drawer and comprising spaced base members connected by cross members and constituting drawer side members, bottom members pivoted between said base members so that they may be adjusted to rest upon said cross members or to an oppositely inclined relation, and end members mounted on said bottom members.

3. A sheet holder adapted as a cabinet drawer and comprising spaced base members connected by cross members and constituting drawer side members, bottom members piv- 130

oted between said base members so that they may be adjusted to rest upon said cross members with their inner ends overlapping or to an oppositely inclined relation with the edge 5 of one abutting the under side of the other, and end members mounted on said bottom members.

4. A sheet holder adapted as a cabinet drawer and comprising base members, bottom members mounted between said base members so that they may be adjusted to a horizontal position or to an oppositely inclined relation, and end members mounted at the outer edges of said bottom members.

10 5. A sheet holder comprising a base and a pair of holder members each including a bottom member and a side member mounted on said base to be adjusted to bring the bottom members to a horizontal position and 20 the side members to a vertical position or to bring the bottom members to an outwardly inclined position and the side members to an inwardly inclined position.

6. A sheet holder comprising a pair of 25 holder members each including a bottom member and a side member mounted to be adjusted to bring the bottom members to a horizontal position and the side members to a vertical position or to bring the bottom members to an outwardly inclined position and the side members to an inwardly inclined position, one of the side members being adjustable to vary its angle relative to its coacting bottom member.

35 7. A sheet holder adapted as a cabinet drawer and comprising a base and a pair of holder members each including a bottom and a side, said holder members being adjustably mounted on said base so that they may 40 be adjusted to constitute the ends and bottom of the drawer or tilted to an oppositely inclined relation.

8. A sheet holder comprising a base and a pair of holder members each including a 45 bottom and a side, said holder members being adjustably mounted on said base so that they may be adjusted to constitute trough-like holder members each adapted to receive sheets.

50 9. In a structure of the class described, the combination of spaced base members connected by cross members, bottom members pivoted between said base members so that they may be adjusted to rest upon said cross members or to an oppositely inclined relation, overlapping plates secured to said bottom members, one of said plates having a pin and the other a longitudinal slot in which said pin is slidably engaged, there, 55 being an offset at the inner end of the slot with which the pin engages when the bottom members are adjusted to their inclined relation, holder side members mounted on said bottom members, one side member being 60 pivoted to the outer edge of one bottom

member for adjustment relative thereto, and a link on said pivoted side member adjustably connected to one of said base members.

10. In a structure of the class described, the combination of spaced base members connected by cross members, bottom members pivoted between said base members so that they may be adjusted to rest upon said cross members or to an oppositely inclined relation, overlapping plates secured to said 70 bottom members, one of said plates having a pin and the other a longitudinal slot in which said pin is slidably engaged, there being an offset at the inner end of the slot with which the pin engages when the bottom members are adjusted to their inclined relation, and holder side members mounted on said bottom members.

11. In a structure of the class described, the combination of spaced base members connected by cross members, bottom members pivoted between said base members so that they may be adjusted to rest upon said cross members or to an oppositely inclined relation, holder side members mounted on said 80 bottom members, one side member being pivoted to the outer edge of one bottom member for adjustment relative thereto, and a link on said pivoted side member adjustably connected to one of said base members.

12. In a structure of the class described, the combination of spaced base members connected by cross members, bottom members pivoted between said base members so that they may be adjusted to rest upon said cross members or to an oppositely inclined relation, and holder side members mounted on 90 said bottom members.

13. In a structure of the class described, the combination of a base, holder bottom members pivoted on said base so that they may be adjusted to a horizontal position with their inner ends overlapping or to an oppositely inclined relation with the edge of one abutting the under side of the other, and holder side members mounted on said bottom members, one side member being fixed to the outer edge of one bottom member and the other being pivoted to the outer edge of the other bottom member for adjustment relative thereto.

14. In a structure of the class described, the combination of a base, holder bottom members pivotally mounted so that they may be adjusted to a horizontal position with their inner ends overlapping or to an oppositely inclined relation, and holder side members mounted to coact with said bottom members.

15. In a structure of the class described, the combination of a base, holder bottom members mounted so that they may be adjusted to a horizontal position or to an oppositely inclined relation, holder side members mounted to coact with said bottom mem- 125
130

bers, one side member being mounted for adjustment relative to its coacting bottom member, and a sheet support adapted to be arranged against one of said end members to support the sheets with their inner edges resting on the bottom at an acute angle thereto.

16. In a structure of the class described, the combination of a base, holder bottom members mounted so that they may be adjusted to a horizontal position or to an oppositely inclined relation, holder side members mounted to coact with said bottom members, and a sheet support adapted to be arranged against one of said end members to support the sheets with their inner edges resting on the bottom at an acute angle thereto.

17. In a structure of the class described, the combination of a base, holder bottom members mounted so that they may be adjusted to a horizontal position or to an oppositely inclined relation, and holder side members mounted to coact with said bottom members.

18. A sheet holder comprising a pair of holder members each including a bottom and a side mounted to be adjusted to bring the bottom members to a horizontal position or to an oppositely inclined position, a sheet guide on one of said bottom members, and a sheet support adapted to be arranged in one of said holder members to support the sheets at an acute angle to the bottom member on which they rest.

19. A sheet holder comprising a pair of holder members each including a bottom and a side mounted to be adjusted to bring the bottom members to a horizontal position or to an oppositely inclined position, and a sheet support adapted to be arranged in one of said holder members to support the sheets at an acute angle to the bottom member on which they rest.

20. A sheet holder comprising a pair of holder members each including a bottom and a side mounted to be adjusted to bring the bottom members to a horizontal position or to an oppositely inclined position, one of the side members being adjustable to vary its angle relative to its coacting bottom member, a sheet guide on one of said bottom members, and a sheet support adapted to be arranged in one of said holder members to support the sheets at an acute angle to the bottom member on which they rest.

21. A sheet holder comprising a pair of holder members each including a bottom and a side mounted to be adjusted to bring the bottom members to a horizontal position or to an oppositely inclined position, one of the side members being adjustable to vary its angle relative to its coacting bottom member, and a sheet support adapted to be arranged in one of said holder members to

support the sheets at an acute angle to the bottom member on which they rest.

22. A sheet holder comprising a pair of holder members each including a bottom and a side mounted to be adjusted to bring the bottom members to a horizontal position or to an oppositely inclined position, one of the side members being adjustable to vary its angle relative to its coacting bottom member, and a sheet guide on one of said bottom members.

23. The combination with loose sheets, of a sheet holder comprising a pair of holder members having side and bottom members disposed at right angles to each other, said sheets being transferable from one holder member to the other, and a tapered support removably associated with said holders and adapted when in operative position to support the sheets in an inclined position with their lower edges abutting the holder bottom member and their upper edges in a stepped relation to facilitate fingering.

24. The combination with loose sheets, of a pair of holder members comprising side and bottom members disposed at right angles, the sheets being transferable from one holder member to the other, and a tapered sheet support adapted to support the sheets with their edges in a stepped relation.

25. The combination of loose sheets, and sheet holder members comprising side and bottom members, the sheets being transferable from one holder member to the other, the side of one holder member being adjustable relative to its bottom, so that it may be adjusted to a position at right angles thereto or to a position at an acute angle thereto, for the purpose specified.

26. In a structure of the class described, the combination of a pair of holder members comprising bottom members pivotally mounted so that they may be adjusted to an overlapping position or tilted outwardly.

27. In a structure of the class described, the combination of a holder comprising bottom members associated so that they may be adjusted to a horizontal position or to an oppositely inclined relation, and side members coacting with said bottom members to provide a pair of opposed sheet holders.

28. A structure of the class described comprising a pair of holder members pivotally mounted so that they may be adjusted to bring parts thereof into an overlapping relation or to an oppositely inclined relation with their edges adjacent and providing a pair of opposed sheet holders.

29. A holder comprising a pair of holder members each having a bottom and a side, the members being adjustably associated so that they may be adjusted to bring the bottom members to a horizontal overlapping position or to an oppositely inclined relation.

30. In a structure of the class described, the combination of a holder comprising bottom members and side members adjustably associated so that they may be adjusted to bring the bottom members to an overlapping relation or to an oppositely inclined relation.

In witness whereof, I have hereunto set

my hand and seal in the presence of two witnesses.
